UNITED STATES PATENT OFFICE.

HOLGER NIELSEN, OF LAWTON, MICHIGAN

GRINDING MACHINE.

Application filed March 9, 1925. Serial No. 14,092.

This invention relates to improvements in grinding machines.

The main objects of this invention are:

First, to provide an improved grinding machine especially adapted for the grinding of valve seats in internal combustion engines.

Second, to provide an improved grinding machine adapted for the grinding of valve seats which is of large capacity and at the same time performs very accurate work.

Third, to provide an improved grinding machine of the class described which is readily adapted to the particular work.

Objects relating to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a detail view partially in section on a line corresponding to line 1—1 of Figs. II and III.

Fig. II is a plan view.

Fig. III is a detail view partially in horizontal section on a line corresponding to line 3—3 of Fig. I.

In the drawing similar reference characters refer to similar parts throughout the several views, and the sectional views are taken looking in the direction of the little arrows at the ends of the section lines.

Referring to the drawing, I provide a frame comprising a top spider-like member 1, posts 2 and 3 rigidly secured thereto, the posts 2 being connected by a cross member 4 at their lower ends while the posts 3 have adjustable arms 5 secured thereto, the cross member 4 and the arms 5 being adapted to rest upon a cylinder block shown conventionally at 6, the arms 5 being adjusted to adapt the frame to the particular cylinder block.

In the structure illustrated, the driving motor 7 is carried by brackets 8 and the cross piece 9 as shown in Fig. I. The tubular tool carriage support 10 is arranged through a central opening 11 in the spider-like top member 1 of the frame and threaded to receive the feed nut 12 which is arranged

in a seat 13 provided therefor. At its lower end this support is provided with a flange 14. The driving spindle 15 is arranged vertically through the support and is provided with a pulley 16 connected by the belt 17 to the motor. At its lower end the spindle 15 is provided with a conical friction driving disc 18. The spindle is supported in an adjustable bearing member 19 slideable in the tubular body of the support and held yielding downward by means of the coiled spring 20. The movement of this bearing member is limited but is sufficient to permit a driving gear 18 being held downwardly under spring tension.

The tool carriage 21 is mounted on the underside of the flange 14, the tool carriage having an upwardly projecting flange 22 embracing the flange 14 and being retained thereon by the ring 23 to the underside of which is secured the annular gear 24, this gear bearing upon the flange 14. The tool carriage is driven from the elongated driving pinion 25 on the spindle, a gear 26 meshing with this pinion and being connected to the gear 27 meshing with the annular gear 24, these gears 26 and 27 being carried by the stub shaft 28 on the flange of the support. Thus arranged, the rotation of the spindle drives the tool carriage.

The grinding tool 29 is carried by the spindle 30, this spindle being carried by the bearing 31 mounted for longitudinal reciprocation in the bracket 32 depending from the tool carriage. This bracket is adjustably mounted on the tool carriage, the bracket being slotted at 33 to receive the screw 34.

The spindle is provided with a driven friction gear 35 coacting with the driving friction gear 18. The gear 18 being conical permits the arrangement of the tool spindle at an angle and maintains the constant driving engagement of the tool spindle gear during the reciprocating movement. The spring 20 also serves to hold the tool to the work. The purpose of reciprocating the tool is to provide for an even wearing of the grinder. Substantially the entire periphery of the gear is brought into action in grinding the valve seat, as is indicated at 36.

To automatically reciprocate the tool spindle, I provide a cam 37 which is mounted upon the tool carriage support to coact with the roller 38 on the inner end of the lever 39 which is pivoted on the tool

carriage at 40 and connected to the spindle supporting bearing by the link 41. A spring 42 moves the spindle in one direction and holds the roller 38 in engagement with the cam.

I provide a pilot or guide 43 which is adapted to engage the valve stem opening in an internal combustion engine, this pilot being carried by the plate 44 which is adapted to rest upon the work. This plate is connected to the carriage to rotate therewith by means of the post 45 comprising telescoping sections or members, the spring 46 being arranged within the post to urge the plate against the work. The plate is provided with a threaded socket 47 which permits the changing of the pilot for work having valve stem openings of different sizes, that is, the pilot should correspond in diameter to the diameter of the valve stem for which the seat is ground.

My improved grinding machine enables very rapid work and also very accurate work. The structure also has the advantage of being simple and economical and easily manipulated.

I have illustrated and described my improvements in an embodiment which I have found practical. I have not attempted to illustrate and describe certain other modifications and adaptations as I believe the disclosure made will enable those skilled in the art to embody or adapt my improvements as may be desired.

Having thus described my invention, what I claim as new and desire to secure by Letters Patent, is:

1. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving pinion, a bearing for said spindle slidable on said support, a spring acting to urge said spindle inwardly, a tool carriage rotatably mounted on said flange on said support and having a downwardly projecting tool spindle bracket thereon, a gear secured to said carriage, gears connecting said driving pinion with said gear on said carriage, a tool spindle provided with a driven friction gear coacting with said driving gear, a positioning pilot, a supporting plate therefor adapted to rest upon the work, and collapsible posts connecting said supporting plate to said carriage.

2. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving pinion, a bearing for said spindle slidable on said support, a spring acting to urge said spindle inwardly, a tool carriage rotatably mounted on said flange on said support, a gear secured to said carriage, gears connecting said driving pinion with said gear on said carriage, a tool spindle provided with a driven friction gear coacting with said driving gear, a positioning pilot, a supporting plate therefor adapted to rest upon the work, and posts connecting said supporting plate to said carriage comprising telescoping sections, said

posts having extending springs arranged therein.

2. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving pinion, a bearing for said spindle slidable on said support, a spring acting to urge said spindle inwardly, a tool carriage rotatably mounted on said flange on said support and having a downwardly projecting tool spindle bracket thereon, a gear secured to said carriage, gears connecting said driving pinion with said gear on said carriage, a tool spindle provided with a driven friction gear coacting with said driving gear, a bearing for said tool spindle reciprocatingly mounted in said bracket, an annular cam on said support, and a lever pivotally mounted on said carriage to coact with said cam and operatively connected to said tool spindle bearing.

3. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving pinion, a bearing for said spindle slidable on said support, a spring acting to urge said spindle inwardly, a tool carriage rotatably mounted on said flange on said support, a gear secured to said carriage, gears connecting said driving pinion with said gear on said carriage, a tool spindle provided with a driven friction gear coacting with said driving gear, a positioning pilot, a supporting plate therefor adapted to rest upon the work, and collapsible posts connecting said supporting plate to said carriage.

4. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving pinion, a bearing for said spindle slidable on said support, a spring acting to urge said spindle inwardly, a tool carriage rotatably mounted on said flange on said support, a gear secured to said carriage, gears connecting said driving pinion with said gear on said carriage, and a tool spindle provided with a driven friction gear coacting with said driving gear.

5. In a valve seat grinding machine, the combination of a frame adapted to rest upon the work, a tubular tool carriage support having a flange at its lower end, a feed nut for said support carried by said frame, a driving spindle disposed through said support and provided with a pulley at its outer end, a conical friction driving gear at its inner end and an intermediate driving support, a tool spindle mounted on said carriage and provided with a driven gear co-acting with said driving gear, driving connections from said spindle to said carriage whereby the carriage is rotated, a positioning pilot, and a supporting plate therefor adapted to rest upon the work and yieldingly connected to said carriage. 70
- 10 6. In a machine of the class described, the combination of a frame adapted to rest upon a cylinder block, a tool carriage support mounted on said frame and provided with a feed means, a driving spindle carried by said support and provided with a conical friction gear at its inner end, a tool carriage rotatably mounted on said support, a tool spindle mounted on said carriage for axial movement, and provided with a friction gear coacting with said driving gear, means for automatically reciprocating said tool spindle. 75
- 15 7. In a machine of the class described, the combination of a supporting frame, a carriage support mounted upon said frame, a feed means for said support, a driving spindle mounted on said support and provided with a driving gear at its inner end, a spring acting to urge said spindle inwardly, a tool carriage rotatably mounted on said flange on said support, a gear secured to said carriage, gears connecting said driving pinion with said gear on said carriage, a tool spindle provided with a driven friction gear coacting with said driving gear, and means for automatically reciprocating said tool spindle. 80
- 20 8. In a machine of the class described, the combination of a supporting frame, a carriage support mounted upon said frame, a feed means for said support, a driving spindle mounted on said support and provided with a driving gear at its inner end, a spring acting to urge said spindle inwardly, a tool carriage rotatably mounted on said support, a tool spindle mounted on said carriage for axial movement, and provided with a friction gear coacting with said driving gear, means for automatically reciprocating said tool spindle as the carriage rotates, and a work positioning pilot operatively associated with said carriage. 85
- 25 9. In a machine of the class described, the combination of a supporting frame, a tool carriage support, feed means for said support, a tool carriage rotatable on said support, a driving spindle on said support provided with a conical driving gear, a tool spindle on said carriage provided with a driven gear coacting with said driving gear, driving connections from said spindle to said carriage whereby the carriage is rotated, and means for automatically reciprocating said tool spindle actuated by the rotation of the carriage. 90
- 30 10. In a machine of the class described, the combination of a supporting frame, a tool carriage support, feed means for said support, a tool carriage rotatable on said support, a driving spindle on said support provided with a conical driving gear, a tool spindle on said carriage provided with a driven gear coacting with said driving gear, driving connections from said spindle to said carriage whereby the carriage is rotated, and means for automatically reciprocating said tool spindle actuated by the rotation of the carriage. 95
- 35 11. In a machine of the class described, the combination of a supporting frame adapted to rest upon a cylinder block, a tool carriage support, feed means for said support, a tool carriage rotatable on said support, a driving spindle disposed centrally and vertically on said support and provided with a driving gear, a tool spindle on said carriage provided with a driven gear coacting with said driving gear, driving connections from said spindle to said carriage whereby the carriage is rotated and a pilot adapted to engage a valve stem opening operatively connected with said carriage. 100
- 40 12. In a structure of the class described, the combination of a tool carriage support provided with feed means, a carriage rotatably mounted on said support, a driving spindle, driving connections from said spindle to said carriage, a tool spindle mounted on said carriage to permit the axial reciprocation of the tool spindle, means for reciprocating said tool spindle actuated by the rotation of the carriage, and driving connections from said tool spindle to said driving spindle permitting the reciprocation of the tool spindle. 105
- 45 13. In a structure of the class described, the combination of a frame, a driving spin- 110
- 50 60 65 70 75 80 85 90 95 100 105 110 115 120 125 130
7. In a machine of the class described, the combination of a supporting frame, a carriage support mounted upon said frame, a feed means for said support, a driving spindle mounted on said support and provided with a driving gear at its inner end, a tool carriage rotatably mounted on said support, a tool spindle mounted on said carriage for axial movement and provided with a driven gear coacting with said driving gear, driving connections from said spindle to said carriage whereby the carriage is rotated, means for reciprocating said tool spindle comprising a cam on said support, and a lever on said carriage coacting with said cam and operatively connected to said spindle, a positioning pilot, and a supporting plate therefor adapted to rest upon the work and yieldingly connected to said carriage. 120
8. In a machine of the class described, the combination of a supporting frame, a carriage support mounted upon said frame, a feed means for said support, a driving spindle mounted on said support and provided with a driving gear at its inner end, a tool carriage rotatably mounted on said support. 125
9. In a machine of the class described, the combination of a frame, a driving spin- 130

dle provided with a conical friction gear, a rotatably mounted tool carriage, a tool spindle mounted on said carriage for axial movement and provided with a friction gear coacting with said driving gear, and means for automatically reciprocating said tool spindle as the carriage rotates.

14. In a structure of the class described, the combination of a frame, a driving spindle, a rotatably mounted tool carriage, a

tool spindle mounted on said carriage for reciprocating movement, driving connections for said tool spindle to said driving spindle and for said driving spindle to said tool carriage, and means for automatically reciprocating said tool spindle.

In witness whereof I have hereunto set my hand.

HOLGER NIELSEN.
